TWO STAGE HAMMER MILL

Woodrow W. West, Rosemont, Pa., assignor to
Pennsylvania Crusher Company, Philadelphia,
Pa., a corporation of New York

Application June 8, 1951, Serial No. 230,622

4 Claims. (Cl. 241—154)

1

This invention relates to an impact type crusher and more particularly to the multiple impact crushing of frangible material by a plurality of separately rotating sets of rotating hammers.

An object of the invention is to provide a crushing machine that reduces frangible material by impact.

Another object of the invention is to reduce frangible material to the desired size by rotating hammers hitting the material repeatedly against breaker surfaces.

Another object of the invention is to provide a machine that may be readily adjusted to accommodate different types of incoming material and reduce it to different desired sizes.

Other and further objects and advantages will be understood from the following description taken in connection with the accompanying drawing.

A crushing machine, as embodied in this invention is shown in the drawing, comprising an outer supporting casing 10 with a feed opening 11 and an exit opening 18. A feed chute 12 in the feed opening 11 delivers material to an initial impact rotor 13 having hammers 22 within a breaker chamber 14 in the casing 10 crushing the material against the walls. An output impact rotor 16 having hammers 23 and positioned in a breaker chamber 17 receives the material from the impact chamber 14 further crushing it. The crushed material drops through 30 exit opening 18 in the bottom of the casing 10 beneath the rotor 16. Impact plates 19 are mounted on the casing 10 forming the upper side of the chamber 14 opposite to the rotor 13, and breaker plates 21 are mounted on the casing 10 forming a side to the breaker chamber 17 opposite the rotor 16. It is a feature of this invention that the rotors 13 and 16 rotate in the same direction in a clockwise direction as shown in the drawing. The incoming material slides into the machine from the delivery slide 12 at the top of the left side and is initially hit by the hammers 22 on the rotor 13 and smashed against the impact plates 19. Some of the fragments from this fracture of the material may drop downward toward the second rotor 16 where they are struck by hammers 23 and impacted against the impact plates 21. Other of the particles striking the impact plates 19 rebound into the path of the hammers 22 of the first rotor 13 and are struck before delivery to the hammers 23 of the second rotor. The particles impacted against impact plates 21 substantially all rebound and are struck by the hammers 23 of the second rotor in their downward movement of 55

2

the right hand side of the cycle of rotation as can be seen in the drawing. The particles are thus thrown against impact plates 21 immediately adjacent to second rotor from which they fall through discharge opening 18 and out of the crusher.

The rotors 13 and 16 are positioned and spaced so that the hammers turn free of one another and the hammer circles do not intersect within each other, thus the hammers 22 and 23 swing freely. The rotor 16 is positioned below and to the right of the rotor 13 so that the material from chamber 14 drops into the hammercircle of the rotor 16. Though they do not intersect the hammercircles may overlap slightly in the vertical plane. In the horizontal plane the hammercircles may overlap even more.

The rotor 13 is keyed to a drive shaft 24 and has a plurality of sets of hammers 22 which may be rigidly secured to discs 26 as shown or of the free swinging type. This construction may be of conventional design. The rotor is positioned near the entrance chute 12 and has its center below the end 27 of the delivery slide. The material coming off the slide 12 is hit by the hammers 22 after the hammers have passed above the center level of the rotor. The outer tips 25 of the hammers 22 describe a hammercircle upon rotation of the rotor 13. The breaker surfaces 31, 34 are spaced from this circle at a distance approximately equal to the radius of the hammercircle. Breaker surfaces 31 and 34 of impact plates 19 are positioned above the hammers 22 and they curve downwardly with a lower portion 29 closer to the hammers 22 than the upper breaker surface 31 to form a converging breaker chamber 14. The delivery slide 12 is set at an angle to the horizontal. The slide is adjustable and may be set at different angles and the end 27 may be raised and lowered so that the speed and angle of entrance of the incoming material into the crusher may be varied and the position and the place where it enters the periphery of the rotating hammers is similarly varied.

The slide 12 is mounted on a pivot 28 near the end 27 and adjustably supported by the crank 30 and lever 33 at the other end. By turning the crank 30 the angle of the slide may be changed. The pivot 28 is mounted on the vertically adjustable pedestal 35 supported by the legs 40 threaded in the beam 49. The pedestal may be raised or lowered to position the edge 27. The material drops from the hopper 47 onto the chute 12 and slides into the rotating hammers 22. The material sliding off the edge 27 is hit by

the hammers 22 adjacent an inner edge 27 and smashed upwardly against the breaker surface 31 and the breaker surface 34 of the impact plates 19. It may thus fall back into the path of the hammers 22. The hammers 22 hit the material again against the breaker surface 29 of impact plates 19. The material then drops into the path 23 of the rotor 16 passing through the breaker chamber 17. Some of the material may be driven initially against the surface 29 and fall directly into the second rotor 16.

The rotor 16 is keyed on the drive shaft 36 and has a plurality of sets of hammers 23 mounted on discs 31. The hammers 23 are of the swinging type hammers pivotally mounted on the pins 38 extending through the discs 31 in a conventional manner.

The material is initially hit by the hammers 23 of the second rotor 16 moving through the quadrant closest to rotor 13 and smashed against a set of breaker surfaces 39 adjacent to the breaker surface 29. These surfaces 39 are above the rotor 16 and approximately an equi-distance from the periphery of the hammers 22 and the periphery of the hammers 23. The material hitting surfaces 39 drops back into the periphery of the hammers 23 and is hit again by the hammers 23 at a point below the breaker plates 39 and smashed against breaker surfaces 41 of the plates 21. Further crushing may occur between the hammers and breaker surfaces 42 below breaker surfaces 41. The crushed material then drops out through the exit chute opening 18. The breaker surfaces 39 are closer to the hammers 23 than the breaker surfaces 31 are to the hammers 22. The breaker surfaces 41 and 42 are even closer to the periphery of the hammers 23 narrowing the passage through the machine and reducing the distance between the plates and hammers.

The breaker plates 19 and 21 are held in position by the stubs 43 extending through the casing and wedges 44 driven through openings in the stubs pulling the stubs tightly against the casing. The plates 19 and 21 are drawn against the casing. The plates 21 engage one another and interlock forming the breaker surface.

The side or end walls of the casing are lined with plates 45 to protect the end walls of the casing. Around the top and side walls of the delivery chute are plates 46 to protect the walls of the casing.

The beam 49 closes the breaking chamber below the chute 12. A sheet metal piece 51 is positioned at a slant between the beam 49 and the opening 18 and is rigidly fastened to the beam 49 and the angle 52 forming an edge of the opening. Material caught or carried in back of the hammers slides down this piece and falls out through the opening. There is no tramp iron pocket. Any unbreakable material passes through the crusher and out the opening 18. With the rotors turning clockwise and downward there is no tendency of tramp iron to become trapped or jammed in the machine.

From the foregoing description it is seen that the rotors 13 and 16 may be set at different speeds. Rotor 13 may rotate faster or slower than rotor 16. The angle and height of the chute 12 may be adjusted to properly introduce the material into the hammercircle of the rotor 13. These adjustments and variations will be made depending on the type and size of material to be reduced and the final sizes desired.

The narrowing of the breaker chamber between

the walls and the hammers, as the material progresses through the machine, increases the number of blows as the material becomes finer and the number of pieces increases so that each small piece will be hit.

Larger pieces of material may be introduced into the crusher and broken to smaller sized pieces than has been heretofore possible. With the rotors independent, their speed may be separately adjusted depending on the type of introduced material and the desired resulting product.

As it is readily apparent that various modifications may be made in the above described embodiment it is intended that the scope of this invention be limited only by the appended claims.

I claim:

1. An impact crusher comprising a first impact rotor having rotatable hammers providing an initial crushing action on material introduced into the crusher and a second impact rotor having hammers rotatable in the same direction as said first rotor hammers, said second rotor being in the immediate vicinity of and in open communication with said first rotor, said second rotor positioned at a lower level than said first rotor and to the side of a vertical plane through the center of said first rotor to receive material subjected to the initial crushing action, means for feeding material substantially radially into the quadrant of the hammercircle of the first rotor in which the hammers are moving upwardly above the level of the center of the rotor, breaker means having a relatively horizontal extending portion spaced above said first rotor to receive radially entering material hit by the upwardly moving first rotor hammers and said breaker means extending in spaced relation above said rotors in an increasingly vertical downward direction to receive the impact of material from said rotors and reflecting the material into the rotating hammers, a substantially vertical extending portion of said breaker means extending downwardly from said increasing vertical portion at the side of said second rotor and spaced therefrom a distance less than the spacing of said first rotor from said horizontal portion to receive the impact of the material hit by said second rotor in the final crushing action.

2. An impact crusher comprising a first impact rotor having hammers providing an initial crushing action on material introduced into the crusher and a second impact rotor in the immediate vicinity of and in open communication with said first rotor and positioned at a lower level than said first rotor and contiguous to a vertical zone through the peripheral edges of the first rotor hammers and to receive crushed material from said first rotor, a feed chute positioned to feed material substantially radially into the intermediate sector of the quadrant of the hammercircle in which the hammers are moving upwardly above the level of the center of the rotor, a breaker surface having a relatively horizontal portion spaced above said first rotor to receive radially entering material hit by the upwardly moving first rotor hammers and said breaker surface extending in spaced relation above said rotors in an increasingly vertical downward direction to receive the impact of material from said rotors and reflecting the material into the hammercircles, a substantially vertically portion of said breaker surface being at the side of said second rotor and spaced therefrom a distance less than the spacing of said first rotor from said horizontal portion to receive the impact of the mate-

rial hit by said second rotor in the final crushing action.

3. An impact crusher comprising a first impact rotor having rotatable hammers providing an initial crushing action on material introduced into the crusher and a second impact rotor having rotating hammers in the immediate vicinity of and in open communication with said first rotor and positioned at a lower level than said first rotor, with the second rotor and the downwardly moving hammers of said first rotor on the same side of a vertical zone through the center of the first rotor to receive material subjected to the initial crushing action, means for feeding material substantially radially into the quadrant of the hammercircle in which the first rotor hammers move upwardly above the level of the center of the rotor, a breaker wall having a relatively horizontal portion spaced above said first rotor to receive radially entering material hit by the upwardly moving first rotor hammers and said breaker wall extending in spaced relation above said rotors in an increasingly vertical downward direction to receive the impact of material from said rotors and reflecting the material into the rotating hammers, said second rotor rotatable in the same direction as said first rotor to hit the material against said breaker wall, a substantially vertical portion of said breaker wall being at the side of said second rotor extending downwardly from said increasing vertical portion and spaced therefrom a distance less than the spacing of said first rotor from said horizontal portion to receive the impact of the material hit by said second rotor in the final crushing action.

4. An impact crusher comprising a first impact rotor having rotatable hammers providing an initial crushing action on material introduced into the crusher and a second impact rotor rotatable in the same direction as said first rotor, said

second rotor being in the immediate vicinity of and in open communication with said first rotor to overlap said first rotor in a horizontal zone and contiguous to a vertical zone through the peripheral edges of the rotating first rotor hammers to receive material subjected to the initial crushing action, an inclined feed chute positioned to feed material substantially radially into the quadrant of the hammercircle in which the hammers are moving upwardly above the level of the center of the rotor, a breaker wall having a relatively horizontal portion spaced above said first rotor to receive radially entering material hit by the upwardly moving first rotor hammers and said breaker wall extending in spaced relation above said rotors in an increasingly vertical downward direction to receive the impact of material from said rotors and reflecting the material into the rotating hammers, a substantially vertical portion of said breaker wall being at the side of said second rotor extending downwardly from said increasing vertical portion and spaced therefrom a distance less than the spacing of said first rotor from said horizontal portion to receive the impact of the material hit by said second rotor in the final crushing action.
